UNITED STATES PATENT OFFICE

2,666,392

PUMP FOR PRECISION ADJUSTMENT

Edward G. Martin, Cambridge, Mass.

Application October 15, 1948, Serial No. 54,694

3 Claims. (Cl. 103—38)

1

The present invention relates to pumps and more particularly to pumps for precision adjustment of the quantity of material handled.

An object of the present invention is to provide a pump particularly suited for laboratory and experimental use in which the fluid handled, whether a liquid or gas, may be precisely adjusted as to quantity.

Another object of the present invention is to provide a pump in which the fluid is scavenged from the cylinder at the end of each stroke regardless of the stroke adjustment.

With this object in view the principal feature of the present invention comprises a reciprocating pump having a linkage for operating the piston arranged so that the stroke may be varied entirely from one end of the cylinder whereby the clearance between the piston and the cylinder, at the end of the stroke is small and substantially uniform. Another feature contemplates means whereby the stroke may be varied even during operation of the pump by simply changing the position of a fulcrum.

In the accompanying drawings Fig. 1 is a side elevation of my preferred form of pump; Fig. 2 is a plan view; Fig. 3 is a section on line 3—3 of Fig. 1; Fig. 4 is a section on line 4—4 of Fig. 1; Fig. 5 is a detail view of the beam; and Fig. 6 is a diagram of the linkage.

The illustrated embodiment of the present invention comprises a pump having a cylinder 6 within which reciprocates a piston 8. At the end of the cylinder is a valve box 10 containing rotary valves of any suitable construction. Connected with the valve box are an inlet port 12 and four outlet ports 14, the latter being under the individual control of manual valves 16. The pump is driven by a motor 18 through a variable speed gear box 20, gears 22 and 24, and a crank shaft 26, the latter passing through the valve box 10 to operate the valves and protruding at the other end for connection with the piston-drive linkages which are shown schematically in Fig. 6.

Referring first to Fig. 1, the crank shaft 26 is provided with a crank 28 connected through a link 29 with a walking beam 30 which extends along the entire side of the pump. The beam 30 is pivoted on an adjustable fulcrum pin 32 which will be described latter. The beam is provided with a long slot 34 to accommodate the pin. The slot extends to the extreme end of the beam, as shown in Fig. 5. The beam is strengthened at its outer end by a yoke member 36 which is spaced away from the beam proper by a sufficient

distance to allow the fulcrum pin 32 to be moved to the extreme end of the beam. The pin 32 is provided with a flange 37 which can be accommodated in the space 38 within the yoke when the fulcrum is at the extreme end of the beam.

Pivoted to the yoke 36 is a link 40 which in turn is pivoted to a bell crank having arms 42 and 44. The bell crank is journaled at a fixed point 45 of the frame. The arm 44 is pivotally connected to a piston-driving link 46 which is connected at 47 to the piston 8 itself.

A link 48 is connected from a fixed point 49 on the frame to the yoke 36.

The fulcrum pin 32 is provided with a stud 50 mounted to slide in a horizontal slot 52 in the frame. A screw 54 threaded through the stud is arranged for rotatable adjustment by a handwheel 56 to permit longitudinal adjustment of the fulcrum. A lock screw 60 is preferably provided for the fulcrum. An index 62 is mounted on the fulcrum and moves over a graduated scale 64.

The operation of the pump is explained in conjunction with the simplified linkage diagram of Fig. 6. In this diagram the various links are shown in single lines, but with the same reference characters as in the actual structure. Certain points are conveniently designated by letters as follows: crankshaft axis A; crank pin B; left end of beam 30, C; connection of link 46 to piston, D; fulcrum 32, E; fixed point 49, F; pivotal connection between 44 and 46, G; right end of beam, H; end of bellcrank arm 42, J; journal 45 mounting for bellcrank, K. For one position of the crank pin B, the foregoing letters are used; for another position certain of the parts are shown in dash lines and the letters are primed.

When the pin B is at its lowermost position, the beam 30 is horizontal and the points C, E, F and H are at that time all in a straight line. Horizontal orientation of the beam 30 is of course not essential but it is necessary that the points C, E, F and H all lie on a straight line, which line coincides with the fulcrum guide slot 52; thus the fulcrum point E, whatever its adjusted position, lies on that line.

For the full-line condition, the piston 8 is at the limit of its compression stroke. When the crank makes a half revolution so that point B is carried into B', the walking beam is tilted about the fulcrum point E so that points C' and H' assume the positions indicated. As a result the piston is brought to the limit of its suction stroke. The position of H' is determined by the fact that 48 is a rigid connection between the

end of the beam and a fixed part of the frame; thus the end of the beam follows a circular arc, of which F is always its center, and the length of the arc is determined by the setting of the fulcrum.

To shorten the stroke of the piston it is only necessary to move the fulcrum E along the horizontal line to any desired point. The point E can in fact be moved to the right until it coincides with H, under which condition the stroke is zero. The zero condition is permitted because the fulcrum pin 32 is adjustable to the extreme end of the beam by reason of the yoke 36.

It will be observed from Fig. 6 that the limit of the compression stroke (shown in full lines) of the piston is always the same, regardless of the setting of the fulcrum; that is, the effect of changing the fulcrum is to only change the suction stroke. Since the full-line position is the position of minimum clearance, this results in a substantially complete scavenging of the pump cylinder on each compression stroke. If the pump is being used to handle several different fluids in succession, as in certain experimental studies in animal aeration, the shift from one fluid to another is accomplished with assurance of satisfactory scavenging.

The stroke may be varied at any time, even when the pump is running, by loosening the lock screw and turning the handwheel to move the fulcrum.

Having thus described my invention, I claim:

1. A pump comprising a cylinder, a piston, a linkage for driving the piston, including a walking beam, a fulcrum therefor, a support for said fulcrum along which the fulcrum is adjustable, a crank for rocking the beam, a link pivotally connected to the beam for actuating the piston, and a rigid member pivotally connected at one end to the beam and at the other end to the support for longitudinally positioning the beam during rocking movement, the fulcrum being adjustable along a line so oriented that the position of the beam is unchanged when the beam is at the limit of its rocking movement on the compression stroke of the piston.

2. A pump comprising a cylinder, a piston, a linkage for driving the piston, including a walking beam, a fulcrum therefor, a support for said fulcrum along which the fulcrum is adjustable,

a crank for rocking the beam, a link pivotally connected to the beam for actuating the piston, and a rigid member pivotally connected at one end to the beam and at the other end to the support for longitudinally positioning the beam during rocking movement, the fulcrum being adjustable along a line so oriented that the position of the beam is unchanged when the beam is at the limit of its rocking movement on the compression stroke of the piston, the beam having a slot for said fulcrum extending to the region of the pivotal connection of the piston-actuating link to permit the fulcrum to be adjusted to a point coaxial with said link pivot to reduce the pump stroke to zero.

3. A pump comprising a cylinder, a piston, a linkage for driving the piston, including a walking beam, a fulcrum therefor, a support for the fulcrum along which said fulcrum is adjustable, a crank and link for rocking the beam, a second link pivotally connected to the beam at a point remote from the crank link for actuating the piston, means independent of said links for longitudinally positioning the beam during rocking movement, a slot in the beam within which the fulcrum is received, and means for adjusting the fulcrum in the support and along the beam to vary the center about which the walking beam is rocked by the crank, the paths of adjustment of the fulcrum in the support and along the beam being coincident when the beam is at the limit of its movement on the compression stroke.

EDWARD G. MARTIN.
